CHILD'S GARMENT

Mabel Sheldrick and Clara E. Benchoff, New York, N. Y.

Application August 10, 1951, Serial No. 241,292

5 Claims. (Cl. 2—80)

This invention relates to improvements in garments and in particular to play-suit or swim suit type garments for infants or children.

It is the principal object of the invention to provide a garment of the type described which, when worn, presents to the child the appearance of an animal or the like, thus providing a novel and pleasing appearance.

Another object of the invention is the provision of a garment of the type described in which the bodice thereof is made in the form of the head of an animal or the like, this bodice portion being given a relatively stiff preformed shape to impart to it a three-dimensional effect, without detracting from the comfort or utility of the garment.

Other objects and advantages of the invention will become apparent in the course of the following specification when taken in connection with the accompanying drawings, in which:

Fig. 1 is a front plan view of the garment made according to the invention;

Fig. 2 is a rear plan view thereof;

Fig. 3 is a side elevational view thereof;

Fig. 4 is a vertical section through the bodice portion of the garment, taken along line 4—4 of Fig. 1; and,

Fig. 5 is a section along line 5—5 of Fig. 1.

While the garment may be made to present the effect of any sort of character such as a clown, fictional character, or the like, the most pleasing and unusual effect appears to be presented when the garment is made in simulation of the entire body of an animal. Accordingly, the drawings illustrate a preferred embodiment in which the garment is imparted with the appearance of an animal.

The garment generally comprises a bodice or upper portion 10 and a trunk or lower portion 11. These portions 10 and 11 are separately made, as will be presently described, and may optionally be made of different fabric materials.

Trunk portion 11 is a tubular form fitting body enclosure which has an open top end 12 and a pair of leg openings 13. Said trunk portion 11 is constructed to extend from the crotch to the upper stomach region of the wearer. As shown in Figs. 2 and 3, the rear upper edge of said trunk portion 11 is preferably cut low so that it is located at the waist of the wearer. The trunk portion 11 may also have a separately inserted trunk panel 14, on the top edge of which it has a width approximately equal to the width of the bodice portion 10 and is attached thereto. This trunk panel 14 may be provided with a shirred portion 15 directly beneath the bodice portion 10 to present the effect of the neck of the animal.

The bodice portion 10 is positioned to be located directly over the chest of the wearer. Said bodice portion 10 is hollow and completely enclosed, consisting of a front wall 16 and a rear wall 17 which are stitched together along their peripheral edges by a continuous line of stitching 28. The rear wall 17 is flat and planar, being thus adapted to lie flush against the chest of the wearer. The front wall 16 is made of a plurality of separate sections of selected lengths and widths which vary to enable portions of front wall 16 to project, thus presenting a three-dimensional effect in the head of the animal. In the embodiment illustrated, the front wall 16 is composed of a pair of identical side sections 18 and a central intermediate section 19. The inner edges of the side sections 18 are cut complementary to the edges of the central section 19, and the matching edges are stitched together along their entire lengths by lines of stitching 20. The central section 19 is made of a length

2

which is appreciably greater than the height of the finished head so that it projects forwardly or bulges at or adjacent the center as indicated at 21 in Figs. 3 and 4. Similarly, the inner central portion of side sections 18 are made of an extended width so that together with the central section 19, a transverse convexity is provided. This presents a distinct relief, in the projecting physiognomy of the animal. The edges of the side and central sections 18 and 19 are selectively cut to control the bulging of the front wall 16 and to locate this bulging in the proper positions for presenting the effect of a protruding nose and the like.

To maintain the proper outward protuberance of the front wall 16 which would tend to collapse or flatten out in use, a lining 22 of relatively rigid material is cut in the same proportions as the front wall 16, is preformed, and is inserted within the interior of the hollow bodice portion 10 in abutment with said front wall 16. As shown in Fig. 5, this lining 22 may be made in three sections 22a, 22b, and 22c which correspond in size and shape to the respective side and central sections of said front wall 16. This lining 22 may be made of any suitable material such as buckram, vinyl plastic or the like. In the manufacturing of swim suits, it is preferred to use a plastic lining since materials such as buckram tend to deteriorate in water. Such suitable material is sufficiently rigid to maintain its shape in use, yet flexible enough to prevent injury to the child in case of a fall, blow on the chest, etc.

A pair of shoulder straps 23 are connected at one end to the side upper edges of the rear wall 17, and are removably joined at their opposite ends to the rear upper edge of the trunk portion 11, as by extending through a loop 24 secured to said rear upper edge. When the garment is worn therefore, these shoulder straps maintain said rear wall 17 in its flat and planar form against the chest of the wearer. The said rear wall 17 thus determines the size of the completed animal head. The protruding form of the front wall 16 is thus determined by the differences in length and width between the sections comprising said front wall and the rear wall 17.

Suitable ornamentation may be provided to enhance the effect of the animal or character. For example, a pair of ears 25 may be added by folding suitably shaped pieces of material and sewing them along their bottom edges at the stitch lines 18 and 20. Similarly, a pair of buttons 26 may be sewn on the front wall 16 to represent a pair of eyes. In a like fashion, members may be added to represent a nose, tongue, tail, etc. The trunk portion 11 may be made of latex, rayon, or other material, adapted for use in water, suitably colored or printed to provide the effect of the animal body. Alternatively, the trunk portion 11 may be made of a rough material to present a fuzzy effect, which material may be internally lined with latex or the like.

While one embodiment of the invention has been shown and described herein, it is obvious that numerous changes and omissions and additions may be made without departing from its scope.

What is claimed is:

1. In a fabric article of manufacture, a face-simulating portion formed as an integral part thereof, said portion comprising a rear support wall of flexible fabric material joined to said article of manufacture, and a flexible fabric front wall secured to said rear wall around its periphery to define a hollow head portion therewith, said front wall being formed of a plurality of joined matching panels of varying lengths and widths joined together along their edges, the over-all area of said front wall being greater than the area of said rear wall to provide a protruding area having the contour of a face, and a single sheet of semi-rigid stiffening material secured within the interior of said hollow head portion in substantial flush abutment with said front wall, said stiffening material having a pre-formed convex shape defining the contour of said face and maintaining the front wall in its protruding form, said sheet being normally shape-retaining and being bendable under pressure.

2. A child's garment simulating the body of an animal or the like, comprising a lower portion encasing the trunk region of the child and a hollow upper portion shaped to

simulate the head of said animal and to cover the chest region of the child, said upper portion made of flexible fabric material stitched along its lower edge to the front upper edge of the lower portion, the upper portion having a front wall cut to protrude forwardly to define the contour of the simulated head, and pre-formed stiffening means of semi-rigid material secured within the hollow upper portion in abutment with said front wall and having a pre-formed shape simulating the front contour of the animal head and being effective to cause the front wall of said upper portion to protrude outwardly, said stiffening means being bendable under pressure.

3. A child's garment simulating the body of an animal or the like, comprising a lower garment portion encasing the trunk region of the child and a hollow upper portion shaped to simulate the head of an animal and to cover the chest region of the child, said upper portion being made of flexible fabric material stitched along its lower edge to the front upper edge of the lower portion, the upper portion having a front wall cut to protrude to define the contour of the simulated animal head and a single sheet of stiffening material secured within said hollow upper portion in flush abutment with said front wall and having a pre-formed convex shape simulating the front contour of the animal head and being effective to maintain the front wall of said upper portion protruding outwardly, said sheet being normally shape-retaining and being bendable under pressure.

4. A child's garment simulating the body of an animal or the like, comprising a lower garment portion encasing the trunk region of the child and simulating the body of an animal, and a hollow upper portion shaped to simulate the head of an animal and to cover the chest region of the child, said upper portion being made of flexible fabric material stitched along its lower edge to the front upper edge of the lower portion, said upper portion being

hollow and having a front and rear wall joined together along their peripheral edges, a pair of shoulder straps connecting said upper and lower garment portions and arranged to hold the rear wall of said upper portion flat against the chest region of the child wearer, the front wall having a greater area than said rear wall and being stitched intermediate its edges to provide forwardly protruding portions which define the contour of the animal face, and a single sheet of semi-rigid stiffening material inserted within the interior of said hollow upper portion and of substantially the same size as said front wall, said sheet being joined to the front and rear walls along their joined peripheral edges and being also connected to the front wall at its stitched portions to lie in flush abutment against the inner surface of said front wall, said sheet being normally shape-retaining, having a pre-formed convex shape defining the animal face and being bendable under pressure.

5. A child's garment according to claim 4 in which the front wall is formed of a plurality of joined matching panels of varying length and widths joined together along their edges, said sheet of stiffening material being also formed of a similar number of matching panels joined together and to the panels of the front wall along their respective edges.
